WITNESS:

BY *Victor J. Evans & Leo.*
ATTORNEY

UNITED STATES PATENT OFFICE

ALFRED W. PERKINS AND JOHN D. FRANÇOIS, OF NEWBURYPORT, MASSACHUSETTS;
SAID FRANÇOIS ASSIGNOR TO SAID PERKINS

BOTTLE ATTACHMENT

Application filed January 21, 1932. Serial No. 588,034.

The invention relates to a bottle attachment and more especially to a combination shield and cap remover for bottles.

The primary object of the invention is the provision of a device of this character wherein the same is of a construction as to permit accommodation of the neck and cap sealed end thereof of a bottle so as to serve as a shield for carriage thereby and when it is desired to open the bottle the cap thereof can be extracted or removed by the use of such shield and in the application of the latter to the bottle it will not detract from the appearance and in fact will add thereto as giving the neck of the bottle a wrapped decorated finish.

Another object of the invention is the provision of a device of this character, wherein the construction thereof is novel in form so that it may be telescoped upon the cap sealed end of a bottle to be carried by the latter and embrace the neck and seal the cap therein and upon removal said device can function as a cap extractor or remover.

A further object of the invention is the provision of a device of this character wherein the same when applied to the neck of a bottle will embrace the same and seal the sealing cap thereof so that the bottle when bearing the device will have a neat and attractive appearance and at the same time the said neck and cap of the bottle will be protected thereby and in the use of said device it may function as a cap remover, the device being serviceable for use in removal of the cap from the bottle bearing such device and after such use the device may be thrown away or destroyed.

A still further object of the invention is the provision of a device of this character which is extremely simple in construction, thoroughly reliable and efficient in its purpose, readily and easily applied to and removed from a bottle, neat and attractive in appearance, and inexpensive to manufacture and install.

With these and other objects in view, the invention consists in the features of construction, combination and arrangement of parts as will be hereinafter more fully described in

detail, illustrated in the accompanying drawing, which discloses the preferred embodiment of the invention, and pointed out in the claim hereunto appended.

In the accompanying drawing:—

Figure 1 is a fragmentary elevation of a bottle showing the device constructed in accordance with the invention carried thereby.

Figure 2 is a view similar to Figure 1 showing the device in vertical section.

Figure 3 is a view similar to Figure 2 with the device removed and in position for removal of the sealing cap of the bottle.

Figure 4 is a perspective view of the device removed from the bottle.

Similar reference characters indicate corresponding parts throughout the several views in the drawing.

Referring to the drawing in detail, A designates generally a portion of a bottle carrying at its mouth a crown cap B which is sealed thereon in the usual well known manner and upon the neck of said bottle A is adapted to be carried the device constituting the present invention and hereinafter fully described.

The device comprises a cylindrical body 5 preferably made from metal of the required thickness and the length of said body may be varied according to the length of the neck of the bottle A. This body 5 has a slightly outwardly curled end 6 and an oppositely inwardly curled bead end 7, while formed in the body 5 slightly removed from the end 7 is a substantially oval-shaped opening 8, the latter being disposed with the length thereof transversely with relation to the body 5 and this opening serves to accommodate the cap B of the bottle A so that the edge portion 9 of the opening will function as a jaw while the opposite edge will function as a fulcrum against the top of the cap B for permitting the convenient removal of such cap from the bottle, the jaw 9 in this use being adapted to engage the crimped edge of the cap B as is clearly shown in Figure 3 of the drawing.

Struck outwardly from the body 5 between the opening 8 and the end 7 and adjacent to the opening is an annular external bead or reinforcing rib 10 which materially strength-

ens the body 5 to assure the functioning of the device as a cap remover. The rib or bead medially with respect to the opening 8 is formed with an outstruck nib 11 which 5 indicates the center of the fulcrum in the use of the device as a cap remover.

The body 5 is normally telescoped over the neck of the bottle A and the rib 10 at its concaved inner portion thereof receives the 10 crimped edge of the cap B so that the said body 5 will be removably latched upon the neck of the bottle A and in this position as shown in Figures 1 and 2 of the drawing, will conceal the said cap B and a portion 15 of the neck of the bottle A will be shielded thereby.

Now when it is desired to remove the cap B from the bottle A the body 5 is slipped off of the neck of the bottle A and brought into 20 position to have the cap fit into the opening 8 so that the edge 9 of said opening will engage with the crimped edge of the cap B and the opposite edge of the opening fulcrumed onto the top thereof with the body 25 in the position as shown in Figure 3 of the drawing. Upon pulling upwardly upon the lower portion of the body 5 when in this position as shown in Figure 3 of the drawing the cap B can be readily extracted from the 30 mouth of the bottle A and thereafter the body discarded or thrown away.

The bead end 7 of the body 5 serves to reinforce the latter in conjunction with the rib 10 which latter avoids the breaking away 35

of the opening 8 at the fulcrumed edge thereof or any bending or collapsing of the body when subjected to pressure in the use thereof for the removal of the cap B from the mouth 70 of the bottle A.

It is contemplated that in the service of the device the same has but a single use, that is to say, it will function to remove the cap from a bottle carrying such device and thereafter under such single use it will become 75 unfit for further use and thus be discarded.

What is claimed is:—

A bottle attachment of the character described comprising a cylinder of uniform cross-sectional diameter and of a size to telescope over a bottle neck, a slightly flared end formed on the cylinder for frictional engagement with said bottle neck, an inwardly directed annular bead at the other end of said cylinder, an annular rib externally formed 80 on the cylinder close to the bead, said cylinder being provided with an elongated opening close to said rib and adapted to accommodate a cap when sealed upon the bottle neck for the removal of said cap on manipulation of the cylinder, and an outstruck nib 85 formed from the cylinder and disposed midway of said opening to indicate the center of the fulcrum action of the cylinder when extracting the cap from the bottle neck. 90

In testimony whereof we affix our signatures.

ALFRED W. PERKINS.
JOHN D. FRANCOIS.
